UNITED STATES PATENT OFFICE.

JOHN CHIESA, OF GARLAND, TEXAS.

DOOR-OPERATING MECHANISM.

Application filed April 14, 1924. Serial No. 706,483.

This invention relates to improvements in doors, gates and the like and has for its object the provision of means for automatically opening and closing a door or gate, the invention being especially designed for use in connection with the doors of garages or other doors or gates through which vehicles are adapted to pass.

The primary object of the present invention is the provision of means whereby a door or gate will be automatically opened by the weight of a vehicle approaching the same so as to permit the vehicle to pass through, together with means whereby the door or gate will be automatically closed after the passage of the vehicle, so that it will not be necessary for the door or gate to be manually opened or closed.

Another object of the invention is the provision of novel operating means of this character which will securely hold the door in closed position when the operating means is not in use and will hold the doors against accidental closing during the passage of a vehicle therethrough.

With the above and other objects in view, the invention further includes the following novel features and details of construction, to be hereinafter more fully described, illustrated in the accompanying drawings and pointed out in the appended claim.

In the drawings:—

Figure 1 is a sectional view showing the doors of a building, such as a garage, equipped with the present invention.

Figure 2 is a vertical sectional view of the same.

Figure 3 is a fragmentary elevation, parts being broken away and others shown in section.

Figure 4 is a detail perspective view of the floating beam.

Figure 5 is an enlarged view of one end partly broken away.

Figure 6 is a fragmentary vertical section showing the manner of mounting one end of the inner platform.

Referring in detail to the drawings wherein like characters of reference denote corresponding parts, the reference character 10 indicates the walls of a building, such as a garage, the doorway of which is closed by doors 11. These doors are secured to and supported by standards 12, the upper ends of which are mounted in bearings 13 and the lower ends in bearings 14, so that the said

standards are capable of rotation to permit opening and closing the doors.

Extending transversely of the doorway is a floating beam 15 which for the sake of lightness may be formed of wood and which has secured to its opposite ends substantially U-shaped plates 16 from which extend trunnions 17. Mounted upon these trunnions are rollers 18, the latter being spaced apart sufficiently to provide an opening 19 for receiving the standard 12, the outer end of the opening being closed by a plate 20 which serves to hold the rollers 18 in place. An apertured lug 21 extends from each of the plates 20, the purpose of which will be hereinafter apparent.

Carried by the floating beam 15 are substantially L-shaped brackets 22 and secured within these brackets is a rod 23, the latter forming a pivot rod which extends through hinged members 24, the rod being held in place by collars 25 at opposite ends thereof. The hinged members 24 extend from the adjacent ends of platforms 26 and 27 which are located respectively upon the outer and inner sides of the doors 11 and as the bar 23 serves to connect the platforms and bar 15 through the medium of the brackets 22 and the hinged members 24, simultaneous movement of the platforms and bar will be effected. The adjacent ends of the platforms are normally held in elevated position by means of springs 28 which have one of their ends connected to the lugs 21 and their opposite ends connected to brackets 29 through the medium of chains 30, so that the tension of the springs may be regulated through the adjustable connection of the chains and brackets 29.

As previously stated, the standards 12 are received within the openings 19 provided between the rollers 18 and these standards are provided with spirals 31. Normally when the adjacent ends of the platforms 26 and 27 are elevated as shown in the drawings, the rollers engage the flat portions of the standards 12 so that the latter are held against rotation, but downward pressure upon the platforms will cause the rollers to engage the spiral portions 31 of the standards and rotate the latter so as to open the doors 11. This downward movement is effected by the weight of a vehicle upon either the platform 26 or the platform 27, the doors being opened to permit of the passage of the vehicle. After the vehicle has passed from the platforms

- and the weight is relieved, the springs 28 will restore the platforms to their normally elevated position, the standards being rotated in a reverse direction to close the doors.
- 5 When the platforms are depressed, the rollers will ride past the spiral portions 31 of the standards and engage the flat portions immediately below so that the doors will be held open during the depressed period of the 10 platform.

In order to permit the opposite ends of the platforms to move when the said platforms are depressed or elevated, the outer end of the platform 26 is mounted for sliding movement as shown at 32, while the outer end of the platform 27 has secured thereto arms or brackets 33 which are provided with eyes 34. A rock shaft 35 passes through the eyes 34 and the opposite ends of this shaft 20 are provided with crank arms 36 which are mounted in bearings 37, so that pivotal and sliding movement is provided for the lower end of the platform 27.

While the invention is shown and described as applied to a pair of doors, it is obvious that it is equally well adapted for use with a single door, or with a gate or gates.

The invention is susceptible of various 30 changes in its form, proportions and minor

details of construction and the right is herein reserved to make such changes as properly fall within the scope of the appended claim.

Having described the invention what is claimed is:—

35 A door operating mechanism comprising spaced rotatably mounted standards, a spiral arranged at the lower end of each standard, a floating beam arranged transversely of the doorway, a pair of spaced rollers carried by each end of the beam and arranged to receive the adjacent spiral therebetween, and actuate the latter to rotate said standards when the beam is moved vertically, resilient means from which said beam is suspended, 40 and normally holding the beam elevated, oppositely inclined platforms arranged at the opposite sides of the beam and having their adjacent ends pivotally connected therewith, means supporting the outer end 45 of one beam for sliding movement, a shaft journaled beneath the outer end of the other platform, crank portions formed on the outer ends of said shaft, and bearings receiving said crank portion to allow the outer 50 end of the last mentioned platform to move horizontally when said platform is depressed.

In testimony whereof I affix my signature.
JOHN CHIESA.
